UNITED STATES PATENT OFFICE.

JOHN E. GARDNER, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

AUTOMATIC TELEPHONE SYSTEM.

Application filed April 5, 1921, Serial No. 458,973. Renewed December 12, 1925.

The present invention relates in general to automatic telephone systems but is more particularly concerned with systems of the type usually installed in factories, mercantile establishments, and the like, such systems being commonly known as private automatic exchanges.

More specifically the invention contemplates an improvement in what is known as transfer or passing call service. This service, as is well known, supplies means whereby when a calling subscriber in the main exchange extends a connection to a subscriber in the private automatic exchange, the called subscriber may, by operating his calling device, transfer or pass the call to the line of another subscriber in the branch exchange.

The object of the invention briefly stated, is to limit and simplify to a large extent the complicated and expensive apparatus heretofore used to give this class of service. The invention as shown is applied to dual connectors though it will be readily apparent that certain other passing call systems may be modified in a similar manner. The simplification is accomplished by making certain relays, which hitherto have been duplicated in both connector switches, common and by so arranging the circuits that these common relays perform their functions for both connectors.

A second object of the invention is to give an improved form of supervision to an operator whereby she is positively notified when the called subscriber answers and when disconnection is effected. The manner in which these and other results are accomplished will be described fully herein-after with reference to the accompanying drawings.

Referring now to the drawings, in Fig. 1 is shown a trunk line incoming to the branch exchange where it terminates in the main dual connector H. This trunk line is of the two way type and is adapted to be seized by the local selector connector repeaters of well known construction. The conductors 100-102, inclusive, are the multiples of the trunk line comprising conductors 5 and 6 which terminate in bank contacts in the outgoing level of these local switches. The main connector H is of the well known

Strowger vertical and rotary type having the usual set of 100 contacts arranged in ten rows or levels. This connector has access to local subscribers' lines such as the one shown at substation A. Substation A is of the usual automatic construction having the rotary line switch C individual to it.

In Fig. 2 at H' is shown the auxiliary connector which is associated with the switch shown at H. The auxiliary connector H' is similar to the connector H and has access in the same manner to local subscribers' lines such as that of the substation A¹. This substation is similar to the one shown at A and also has the individual line switch C¹ associated with it.

Figs. 3 and 4 show a certain modification of the invention which is adapted to be used when two called subscribers are desired on the line at one time. Substations A² and A³ are called substations similar to the substation A, and having the individual line switches C² and C³ associated with them.

In Fig. 5 is shown the manner in which the test contacts of the connector switches are connected in order to secure rotary service, that is, to enable the connector switches to be able to pick out an idle line in a group of lines, or if all lines in the group are busy to return the busy signal to the calling subscriber.

Having briefly described the apparatus shown in the drawings, the detailed operation of the same will now be explained. For this purpose it will be assumed that a calling subscriber in the main exchange desires to call the subscriber at substation A in the branch exchange and that he has operated various selectors and a selector repeater in the main exchange in order to connect with an idle trunk line extending to the private automatic exchange which, we will assume, is the trunk line shown in the drawings comprising conductors 5 and 6. When this occurs a circuit will be completed for the line relay 14 of the main connector H over the two sides of the trunk line in series. Relay 14 upon energizing, completes a circuit for the slow acting relay 200 over a circuit extending from ground by way of armature 30 and its front contact, conductor 111, and thence through the winding of the slow acting release relay 200 to battery.

Relay 200 upon operating, at its armature 216 prepares the operating circuits of the main connector H, at armature 215 places ground on release trunk conductor 115, and at armature 217 places ground on release trunk conductor 101 which extends to multiplied test contacts in the banks of the local connector selector repeaters whereby the incoming trunk line comprising conductors 5 and 6 is prevented from being seized by a local subscriber.

The calling subscriber in the main exchange may now operate his calling device in accordance with the next digit of his desired number. By this operation a series of interruptions is produced in the circuit of the line relay 14 of the main connector H which deenergizes a plurality of times in response thereto. At each deenergization an impulse of current is sent over the following path: Ground by way of armature 30 and its back contact, conductor 110, armature 216 and its front contact, conductor 119, off normal springs 74 and 73, winding of the vertical magnet 60, back contact and armature 47, conductor 122, and thence through the winding of the slow acting relay 202 to battery. Upon the first vertical step of the connector H, the off normal springs are shifted and the remaining impulses to the vertical magnet traverse a different circuit which is the same as the one previously traced except that it includes the off normal springs 74 and 75, conductor 118, armature 226 and its front contact, and conductor 117, relay 202 being now in an operated position. The vertical magnet 60 operates to raise the switch wipers 80-83, inclusive, step by step until they are placed opposite the level of bank contacts in which is located the contact set associated with the line of the substation A. The slow acting relay 202 is energized in series with the vertical magnet and retains its armatures attracted throughout the vertical movement of the switch and at the termination thereof deenergizes and transfers the operating circuit to the rotary magnet 61.

The calling subscriber in the main exchange may now operate his calling device in accordance with the next and final digit of his desired number. As before, another series of interruptions is produced in the circuit of the line relay 14 which deenergizes a corresponding number of times. At each retraction of its armature 30, an impulse of current is sent to the rotary magnet 61 over a circuit extending from ground by way of armature 30 and its back contact, conductor 110, armature 216 and its front contact, conductor 119, off normal springs 74 and 75, conductor 118, armature 226 and its back contact, conductor 120, working contact of off normal spring 71 and the said spring, conductor 121, back contact and

armature 230, at which point the circuit divides, one path extending through the winding of the slow acting relay 204 and thence to battery by way of armature 220 and its back contact, and the other path extending by way of conductor 135, armature 49 and its back contact, and thence through the rotary magnet 61 to battery. The rotary magnet 61 operates to rotate the switch wipers 80-83, inclusive, into engagement with the bank contacts associated with the line of the substation A which, we will assume, are the bank contacts 91-94, inclusive. The slow acting relay 204 is energized in multiple with the rotary magnet and operates its armature 237 to connect the test wiper 82 with the winding of the test relay 203.

It will first be assumed that the line of the desired substation is busy at this time. Under these conditions there will be a ground potential present upon the test contact 93 engaged by the test wiper 82 and a circuit will be completed extending from the said grounded test contact, by way of test wiper 82, conductor 140, armature 237 and its front contact, and thence through the winding of the test relay 203 to battery. The relay 203 is energized over this circuit and upon operating, establishes a locking circuit for itself at armature 232 which extends from ground on release trunk conductor 115, off normal spring 70 and its working contact, conductor 114, off normal spring 268 and its resting contact, normally closed springs controlled by armature 223, armature 232 and its front contact, normally closed springs controlled by armature 237, and thence through the winding of the test relay 203 to battery. Another result of the energization of relay 203 is that the busy tone is applied to the line of the calling subscriber over a circuit extending from the busy machine by way of front contact and armature 233, armature 227 and its back contact, conductor 126, and thence to the lower trunk conductor 6. This tone is audible to the calling subscriber and he will replace his receiver upon the switchhook thereby opening the circuit of the line relay 14 in the main connector H which immediately deenergizes opening the circuit of the slow acting relay 200. Relay 200 upon deenergizing, completes a circuit extending from ground by way of armature 30 and its back contact, conductor 110, armature 216 and its back contact, conductor 116, off normal spring 72 and its working contact, and thence through the winding of the release magnet 62 to battery. The release magnet 62 operates to restore the main connector H to normal. Upon ground being removed from the release trunk conductor 115 at armature 215 of the slow acting release relay 200 the locking circuit of the

test relay 203 is opened and this relay consequently deenergizes.

The above is the normal operation of the connector H when a busy line is called provided it is a private line. However, should it be one of a group of lines, the test contacts thereof will be connected in the manner shown in Fig. 5, that is, the test contacts 92 and 93 will be connected together, and therefore ground will be present upon both these test contacts. The operation in this case is somewhat different from that above described and will now be explained. When the test relay 203 energized it prepares a circuit for the stepping relay 201 at armature 231. Then, following the deenergization of the slow acting relay 204, a circuit is effective extending from ground on test contact 92, by way of test wiper 81, armature 46 and its back contact, conductor 137, armature 235 and its back contact, conductor 131, armature 51 and its back contact, armature 79 and its back contact, conductor 133, front contact and armature 231, through the winding of the stepping relay 201 and thence through the winding of the slow acting relay 202 to battery. The relays 201 and 202 are energized over this circuit. Relay 201 upon energizing, establishes a locking circuit for itself at armature 218 and at armature 219 completes the rotary magnet circuit over the path extending from ground by way of front contact and armature 219, conductor 135, armature 49 and its back contact, and thence through the winding of the rotary magnet 61 to battery. The rotary magnet 61 operates to rotate the switch wipers 80-83, inclusive, into engagement with the next set of bank contacts. It will be seen that the slow acting relay 204 is not energized in multiple with the rotary magnet at this time as its circuit is broken at armature 220 of the stepping relay 201. The rotary magnet 61 upon operating also opens the locking circuit of the relays 201 and 202. Relay 201 upon deenergizing, opens the circuit of the rotary magnet. The further operation of the connector H depends upon whether or not the line with which the switch wipers are now associated is or is not busy. If busy, there will be a ground potential present upon the test contacts engaged by test wipers 81 and 82 and the test relay 203 will be maintained energized as the test wiper 82 is maintained in connection with it at armature 225 of the slow acting relay 202. The circuit of stepping relay 201 will again be completed and the relay will operate in the same manner as before to close the circuit of the rotary magnet 61. The alternate operation of the stepping relay 201 and the rotary magnet 61 will continue until an idle line is found or until the switch wipers 80-83, inclusive, are rotated into engagement with the last

line of the group. If rotated into engagement with the last contact set of the group there will be a ground potential only present upon the test contact engaged by test wiper 82, the test relay 203 will be maintained energized, but the stepping relay 201 will not be operated. A busy tone will now be given to the calling subscriber in the same manner as was before described.

It will now be assumed that the line of the substation A was idle when connection thereto was attempted by connector H. Under these conditions there will be no ground present upon the test contact 93 engaged by the test wiper 82 and no circuit will be completed for the test relay 203. Then, following the deenergization of the slow acting relay 204, a circuit is completed extending from ground on release trunk conductor 115, off normal spring 70 and its working contact, conductor 114, off normal spring 268 and its resting contact, normally closed springs controlled by armature 225, armature 232 and its back contact, conductor 138, upper winding of the switching relay 16, back contact and armature 48, conductor 136, back contact and armature 237, conductor 140, normally closed springs controlled by armature 53, test wiper 82, test contact 93, through the winding of the switching relay 96 of the individual line switch C, and thence through the winding of the magnet 97 to battery. The relays 16 and 96 are energized over this circuit. However, due to a mechanical interlocking device controlled by the armature of the line relay which is now normal the relay 96 is only operated enough to disconnect the line of the substation A from its normal battery and ground connections in the line switch C. Relay 16, upon energizing, establishes a locking circuit for itself at armature 50 which extends from ground on release trunk conductor 101 by way of the back contact and armature 67, armature 50 and its front contact, and thence through the lower winding of the switching relay 16 to battery. Relay 16 upon energizing, also transfers the operating circuits of the main connector H to the auxiliary connector H' at armatures 47, 48, 49 and 51, and at armatures 45 and 52 completes the ringing circuit of the substation A. Ringing current is now intermittently projected over the line of the called substation until an answer is obtained. When this occurs the ring cut off relay 15 will be energized over the called subscriber's line loop. Upon operating, this relay at armature 36 establishes a locking circuit for itself and at armatures 34 and 39 opens the ringing circuit and at the front contacts of these armatures finally completes the talking connection. The back bridge relay 13 is energized over the called subscriber's line loop and upon operating, com-

pletes circuits for the slow acting relay 12 and the slow acting relay 11. Relay 12 upon energizing, places the operating circuits of the auxiliary connector H' under control of the called subscriber. Relay 11 upon energizing, reverses the battery over the incoming trunk conductors whereby an operator is given supervision or a meter on the calling subscriber's line operated. Conversation may now be carried on between the calling and called subscribers, battery being supplied to the calling party in the main exchange from the windings of the line relay of the selector repeater and to the called subscriber's line from the windings of the back bridge relay 13. When the conversation is terminated both subscribers will replace their receivers upon the switchhooks and the release of the main connector H will be accomplished when the subscriber at the calling substation in the main exchange replaces his receiver in the same manner as was described hereinbefore.

When the called subscriber at substation A answers he may find it necessary to transfer the calling subscriber to some other party in the private automatic exchange, such as the subscriber at substation A'. In order to do this he will operate his calling device for the digits of that local subscriber's number. By this operation a series of interruptions is produced in the circuit of the back bridge relay 13 which deenergizes a plurality of times in response thereto. At each retraction of its armature 27, an impulse of current is sent over the following circuit: From ground by way of armature 27 and its back contact, armature 26 and its front contact, armature 40 and its front contact, conductor 141, off normal springs 273 and 274, winding of the vertical magnet 261 of the auxiliary connector H', conductor 123, front contact and armature 47, conductor 122, and thence through the winding of the slow acting relay 202 to battery. The above is the circuit over which the first impulse to the vertical magnet 261 is transmitted. Upon the first vertical step of the shaft, the off normal springs are operated and the remaining impulses to the vertical magnet traverse a different circuit which is the same as the one previously traced except that it includes the off normal springs 273 and 274, and armature 226 and its front contact, relay 202 being now in its operated position. Magnet 261 operates to raise the switch wipers 280-283, inclusive, step by step until they are placed opposite the level of bank contacts in which is located the bank contacts associated with the line of the called substation. The slow acting relay 202 is energized in series with the vertical magnet 261 and maintains its armatures attracted throughout the vertical movement of the switch and at its termina-

tion deenergizes transferring the impulsing circuit to the rotary magnet 262.

The first called subscriber at substation A may now call the final digit of the desired called subscriber's number. As before a series of interruptions is produced in the circuit of the back bridge relay 13 which retracts its armature a plurality of times in response thereto, each time sending an impulse of current over the following circuit: From ground, by way of armature 27 and its back contact, armature 26 and its front contact, armature 40 and its front contact, conductor 141, off normal springs 273 and 274, armature 226 and its back contact, conductor 120, working contact of off normal springs 71 and the said spring, conductor 121, back contact and armature 230, where the circuit divides one path extending through the winding of the slow acting relay 204 to battery by way of armature 220 and its back contact, the other path extending by way of conductor 135, armature 49 and its front contact, conductor 134, off normal spring 271 and its working contact, armature 254 and its back contact, and thence through the winding of the rotary magnet 262 to battery. The rotary magnet 262 operates to rotate the switch wipers 280-283, inclusive, step by step until they are placed into engagement with the set of contacts in which is terminated the line of the called substation and which we will assume are the bank contacts 293-296, inclusive. The slow acting relay 204 is energized in multiple with the rotary magnet and operates to connect the test wiper 282 to the test relay 203 at armature 237.

Should this called line be busy at this time there will be a ground potential present upon the test contact 295 engaged by the test wiper 282. A circuit will then be completed extending from the said grounded test contact by way of the test wiper 282, normally closed springs controlled by armature 252, armature 237 and its front contact, and thence through the winding of the test relay 203 to battery. The relay 203 is energized over this circuit and upon operating establishes a locking circuit for itself at armature 232 which extends from ground on release trunk conductor 115, off normal spring 70 and its working contact, conductor 114, off normal spring 268 and its working contact, normally closed springs controlled by armature 225, armature 232 and its front contact, normally closed springs controlled by armature 237 and through the winding of the test relay 203 to battery. Relay 203 upon energizing, also places the busy tone upon the calling subscriber's line over a circuit extending from the busy machine by way of front contact and armature 233, armature 227 and its back contact, conductor 126, and thence to the lower talking con-

ductor 6. This tone is audible to the calling subscriber in the main exchange and to the called subscriber at substation A. The first called subscriber may now communicate 5 with the original calling subscriber in order to ascertain whether or not he desires to obtain connection with another subscriber in the branch exchange. Should this be the case the called subscriber at substation A 10 will replace his receiver upon the switchhook thereby opening the circuit of the slow acting relay 12. The circuit of the supervisory control relay 11 will not be opened at this time as there is a locking circuit completed 15 for the relay 17 immediately upon the auxiliary connector H' stepping off normal and as this relay completes a circuit of the supervisory control relay 11 the latter relay will not be deenergized at this time. The circuit over which the relay 17 is energized extends from ground on release trunk conductor 115, by way of armature 242 and its back contact, working contact of off normal spring 269 and the said spring, conductor 125, normally closed springs controlled 20 by armature 19, and thence through the winding of the relay 17 to battery. Relay 17 upon energizing, establishes a locking circuit for itself at armature 19 which extends 25 from ground on release trunk conductor 115 by way of armature 242 and its back contact, conductor 141, armature 19 and its front contact, and thence through the winding of relay 17 to battery. Relay 17 upon 30 operating, also completes the locking circuit of the supervisory control relay 11. This extends from ground by way of front contact and armature 18, front contact and armature 22, and thence through the winding 35 of the slow acting relay 11 to battery. The slow acting relay 12 upon deenergizing completes a circuit which extends from ground by way of armature 27 and its back contact, armature 26 and its back contact, 40 armature 37 and its front contact, conductor 127, armature 253 and its back contact, working contact of off normal spring 270 and the said spring, and thence through the winding of the release magnet 260 to battery. Magnet 260 operates to restore the auxiliary dual connector H' to normal. Immediately upon the off normal spring 268 breaking away from its working contact the 45 circuit of the test relay 203 is opened and this relay then deenergizes removing the busy tone from the calling subscriber's line. The called subscriber at substation A may now take off his receiver and operate his calling device in accordance with the digits 50 of the number of the next subscriber desired. The auxiliary connector H' will be operated in the same manner as was before described into connection with the line.

55 Returning now to the operation of the auxiliary connector H' when a busy line was

encountered its operation will be described when the busy line called was one of a group of lines. Under these conditions when the wipers 280-283, are rotated into engagement with the bank contacts 293-296, inclusive, there will be a ground potential present upon both test contacts 294 and 295. The test relay 203 will be energized and will operate to establish a locking circuit for itself and to prepare the circuit of the stepping relay 201. Following the deenergization of relay 204, a circuit may be traced extending from the said grounded test contact 294, test wiper 281, armature 251 and its back contact, armature 235 and its back contact, conductor 131, armature 51 and its front contact, conductor 132, back contact and armature 277, front contact and armature 231, through the winding of the stepping relay 201 and through the winding of the slow acting relay 202 to battery. Relays 201 and 202 are energized over this circuit. Relay 201 upon operating, establishes a locking circuit for itself at armature 218 and at armature 219 completes a circuit extending 75 from ground, by way of front contact and armature 219, conductor 135, armature 49 and its front contact, conductor 134, off normal spring 271 and its working contact, armature 254 and its back contact, and through the winding of the rotary magnet 262 to battery. Magnet 262 will operate to rotate the switch wipers 280-283, inclusive, into engagement with the next set of bank contacts and to break the locking circuit of the relays 201 and 202 at armature 277. Relay 201 will immediately deenergize breaking the circuit of the rotary magnet which deenergizes also. The further operation of the auxiliary connector switch H' will take 80 place in the same manner as was described in connection with the connector switch H seeking an idle line.

Returning now to the operation of the auxiliary connector switch H' when connection was made with the line of the called substation A¹, it will now be assumed that this line was idle. Under these conditions, there will be no ground potential present upon the test contact 295 engaged by the test wiper 282 and no circuit will be completed for the test relay 203. Then, following the deenergization of the slow acting relay 204, a circuit may be traced extending from ground on release trunk conductor 115 by way of off normal spring 70 and its working contact, conductor 114, off normal spring 268 and its working contact, normally closed springs controlled by armature 225, armature 232 and its back contact, upper winding of the switching relay 206, conductor 139, front contact and armature 48, conductor 136, back contact and armature 237, normally closed springs controlled by armature 252, test wiper 282, test contact 295, winding 85 90 95 100 105 110 115 120 125 130

6
of the switching relay 298 of the line switch C', and through the winding of the stepping magnet 299 to battery. Relays 206 and 298 are energized over this circuit. 5 However, due to a mechanical interlocking device controlled by the armature of the line relay, switching relay 298 is only partially operated in order to disconnect the line of the called substation A' from its normal 10 battery and ground connections in the line switch C'. Relay 206 upon energizing, establishes a locking circuit for itself at armature 255, over a circuit that extends from ground on release trunk conductor 101 15 by way of armature 266 and its back contact, armature 255 and its front contact, and through the winding of relay 206 to battery. Relay 206 upon operating, also completes the ringing circuit of the called 20 subscriber at substation A' whereby ringing current is intermittently projected over the called line until an answer is obtained. When this occurs a circuit of the ring cut off relay 205 will be completed. This relay 25 upon energizing establishes a locking circuit for itself at armature 241 and at armatures 240 and 245 opens the ringing circuit and at the front contacts of these armatures finally completes the talking connection. 30 Another result of the energization of relay 205 is that a circuit is completed extending from ground by way of front contact and armature 35, conductor 129, front contact and armature 244, armature 265 and its 35 back contact, conductor 116, off normal spring 72 and its working contact, and through the winding of the release magnet 62 to battery. Magnet 62 operates to restore the main connector H to its normal 40 position. Immediately upon the release magnet operating the locking circuits of the ring cut off relay 15 and the switching relay 16 are opened and the switch wipers 80-83, inclusive, are disconnected from the 45 talking conductors of the main connector.

Before proceeding further it will be necessary to know certain adjustments of the armatures on the ring cut off relay 205; the armature 244 is adjusted to close its working 50 contact a short interval before the armature 243 engages its working contact. This provision is made so as to secure the release of the proper switch upon the called subscriber at substation A' answering. It will be apparent 55 that the circuit of the release magnet 62 will be closed at the armature 244. This magnet upon operating, then opens the circuit which would extend from ground by way of back contact and armature 66, armature 38 and its front contact, conductor 128, armature 243 and its front contact, working contact of off normal spring 270, and thence through the winding of the release magnet 260 to battery, thereby securing the 60 release of the main connector H and pre-

venting the release of the auxiliary connector H'. On the ring cut off relay 15 the armature 38 is adjusted to engage its working contact a short interval before the armature 35 engages its working contact. This is in order to secure the release of the auxiliary connector H' when a call is being transferred from a subscriber called by the auxiliary connector H' to a subscriber called by means of the main connector H 75 when the last called party answers.

Should the subscriber at substation A replace his receiver upon the switchhook after connection is made with the line of the substation A' and before that subscriber 80 answers the back bridge relay 13 will be deenergized and the circuit of the slow acting relay 12 opened. A circuit may then be traced extending from ground by way of armature 27 and its back contact, armature 26 and its back contact, armature 37 and its front contact, conductor 127, armature 253 and its front contact, conductor 116, off normal spring 72 and its working contact, and thence through the winding of the 85 release magnet 62 to battery. The main connector H is thereupon released. It will be noted that upon the back bridge relay 13 deenergizing, the original energizing circuit of the supervisory control relay 11 is 90 opened. However, this relay does not deenergize at this time for the reason that its locking circuit is completed by relay 17 which is now energized.

Returning now to the operation of the auxiliary connector H' when the ring cut off relay 205 energized the locking circuit of the relay 17 was opened at armature 242 and this relay then deenergized opening the locking circuit of the supervisory control relay 11 but the latter relay does not deenergize at this time for the reason that a circuit is completed by the back bridge relay 13 which is energized over the line loop of the called subscriber at substation A'. Conversation may now be carried on over the heavy talking conductors, between the original calling subscriber in the main exchange and the called subscriber at substation A' battery being supplied to the calling subscriber from the windings of the line relay of the selector repeater in the main exchange and to the called subscriber from the windings of the back bridge relay 13. When the conversation is terminated 110 the release of the dual switches will take place in the same manner as was before described.

In order to describe the operation of the dual switches when the call is transferred by means of the main connector H it will be assumed that the subscriber at substation A' desires to transfer the call to another party in the branch exchange. In order to do this he will operate his calling device 125 130

in accordance with the digits of this local subscriber's number. Upon the first operation of the calling device at substation A', a series of interruptions is produced in the 5 circuit of the back bridge relay 13 which deenergizes a corresponding number of times. At each deenergization an impulse of current is sent over the following circuit: Ground by way of armature 27 and its 10 back contact, armature 26 and its front contact, armature 40 and its back contact, off normal springs 74 and 75, winding of the vertical magnet 60, back contact and armature 47, conductor 122, and through the 15 winding of the slow acting relay 202 to battery. The above is the circuit over which the first impulse is sent to the vertical magnet. Upon the first vertical step of the switch the off normal springs are operated 20 and the remaining impulses to the vertical magnet travel over a new circuit which is the same as that previously traced except that it includes the off normal springs 74 and 75, conductor 118, armature 226 and its front contact, and conductor 117, 25 relay 202 being in an operated position. The vertical magnet 60 operates to raise the switch wipers 80—83, inclusive, step by step until they are raised opposite the level of 30 bank contacts in which is located the bank contacts associated with the line of the desired substation. Slow acting relay 202 is energized in series with the vertical magnet and maintains its armatures attracted 35 throughout the vertical movement of the switch and upon its termination deenergizes and transfers the impulsing circuit to the rotary magnet 61. Upon the first vertical step of the main connector H a circuit may 40 be traced extending from ground on release trunk conductor 115, armature 33 and its back contact, working contact of off normal spring 69 and the said spring, conductor 141', working contact of off normal spring 269 and the said spring, conductor 125, 45 normally closed springs controlled by armature 19, and thence through the winding of relay 17 to battery. Relay 17 upon energizing, establishes a locking circuit for itself at 50 armature 19 and at armature 18 completes a locking circuit of the supervisory control relay 11. In this manner the supervisory control relay 11 is locked energized until the subscriber called by means of the 55 main connector H has answered.

The subscriber at substation A' may now operate his calling device in accordance with the next digit of his desired number. As before, a series of interruptions is produced 60 in the circuit of the back bridge relay 13 and it deenergizes a plurality of times in response thereto. At each retraction of its armature 27 a circuit may be traced extending from ground by way of armature 27 and its back contact, armature 26 and its front 65 contact, armature 40 and its back contact, off normal springs 74 and 75, conductor 118, armature 226 and its back contact, conductor 120, working contact of off normal spring 71 and the said spring, conductor 121, back contact and armature 230, conductor 135, armature 49 and its back contact, and through the winding of the rotary magnet 61 to battery. Magnet 61 operates to rotate the switch wipers 80—83, inclusive, into engagement with the set of bank contacts associated with the desired line. Slow acting relay 204 is energized in multiple with the rotary magnet and operates to connect the test wiper 82, to the test relay 203. It 70 will be assumed that the line of the called substation is idle. Under these conditions there will be no ground potential present upon the test contact engaged by the test wiper 82 and following the deenergization 75 of the slow acting relay 204 a circuit is completed extending over the following path: From ground on release trunk conductor 115, off normal spring 70 and its front contact, conductor 114, off normal 80 spring 268 and its working contact, normally closed springs controlled by armature 225, armature 232 and its back contact, conductor 138, upper winding of the switching relay 16, back contact and armature 48, conductor 136, back contact and armature 237, conductor 140, normally closed springs controlled by armature 53, test wiper 82, test 85 contact of the called line, through the winding of the switching relay of the line switch 90 associated with the called substation and thence through the winding of the stepping magnet to battery. The switching of the called line switch operates to clear the called line of its normal battery and ground connections. Relay 16 upon energizing, establishes a locking circuit for itself at armature 50 and at armatures 45 and 52 completes the ringing circuit. Ringing current 95 is now projected out over the called line in the same manner as was before described. When an answer is obtained ring cut off relay 15 is energized and a circuit is completed extending from ground by way of 100 back contact and armature 66, armature 38 105 and its front contact, conductor 128, armature 243 and its front contact, working contact of off normal spring 270 and the said spring, and through the winding of the release magnet 260 of the auxiliary connector H' to battery. Release magnet 260 upon operating, restores the auxiliary connector H' to normal. Relay 15 upon energizing, also opens the locking circuit of the relay 17 at armature 33. 110 Conversation may now take place between the calling and called subscribers over the heavy talking conductors and when this is 115 terminated both parties will replace their receivers upon the switch-hook and the dual 120

connector H will be released upon the calling subscriber replacing his receiver upon the switch-hook in the usual manner.

Had the called line been busy when the 5 main connector H was operated into engagement therewith the same operations would take place as was described before.

As before mentioned the incoming trunk line comprising conductors 5 and 6 is a two 10 way trunk line and may be used for outgoing calls to the main exchange. When this trunk line is seized by a local connector selector repeater ground is placed on the release trunk conductor 101 which extends by 15 way of armature 217 and its back contact, conductor 112 through the winding of the cut off relay 10 to battery. Relay 10 energizes and disconnects the incoming trunk line from the dual connectors H and H' and 20 transfers it to the outgoing multiples 100 and 102. A call may now be made over the trunk line in the usual automatic manner which need not be described.

Having described the operation of the 25 dual connectors H and H', Figs. 1 and 2, the operation of the modification shown in Figs. 3 and 4 will now be discussed. For this purpose it will be assumed that a calling subscriber in the main exchange desires to 30 call the substation A² in the private automatic exchange, and it will be assumed further that he has operated various switches in the main exchange and finally connected to the trunk line comprising conductors 305 35 and 306 which terminates in dual connectors H² and H³ in the private automatic exchange. When this occurs the circuit of the line relay 314 will be completed over the two sides of the incoming trunk line in series. 40 Relay 314 upon energizing, completes the circuit of the slow acting release relay 315 which operates to prepare the impulsing circuits of the main dual connector H² at armature 337 and at armature 338 grounds the 45 release trunk conductor 376 whereby the multiples of the incoming trunk line in the banks of the local connector selector repeaters are busied in order to prevent their seizure for outgoing calls to the main exchange.

The calling subscriber may now operate his calling device in accordance with the 50 next digit of the desired called subscriber's number. By this operation a series of interruptions is produced in the line relay circuit which deenergizes a corresponding number 55 of times each time sending an impulse of current over the following path: Ground by way of armature 334 and its back contact, 60 armature 337 and its front contact, off normal springs 368 and 367, winding of the vertical magnet 357, back contact and armature 328, conductor 417, and thence through the 65 winding of the slow acting relay 513 to battery. The above is the circuit over which

the first vertical impulse is sent. Upon the first vertical movement of the switch the off normal springs are shifted and the remaining impulses to the vertical magnet traverse a new circuit which is the same as the one 70 previously traced except that it includes the off normal springs 368 and 369, conductor 421, armature 531 and its front contact, and conductor 422, relay 513 being now in an operated position. The vertical magnet 357 75 operates to raise the switch wipers 380-383, inclusive, step by step until they are placed opposite the level of bank contacts in which is located the contact set associated with the line of the substation A². The slow acting 80 relay 513 is energized in series with the vertical magnet and maintains its armature attracted during the vertical movement of the switch and at its termination deenergizes transferring the operating circuit to the rotary magnet 355.

The calling subscriber in the main exchange may now call the next and final digit of his desired number. As before, the line 85 relay 314 retracts its armature a plurality of times in response to the interruptions in its line circuit. At each retraction of its armature 334 an impulse of current is sent over a circuit extending from ground by way of armature 334 and its back contact, front contact and armature 337, off normal springs 368 and 369, conductor 421, armature 531 and its back contact, conductor 420, working contact of off normal spring 366 and the 90 said spring, conductor 432, armature 541 and its back contact, where the circuit divides one path extending through the winding of 95 the slow acting relay 516 and thence to battery by way of back contact and armature 527 and the other path extending over conductors 429, armature 349 and its back contact, and through the rotary magnet 355 to 100 battery. Magnet 355 operates to rotate the switch wipers step by step until they are placed in engagement with the set of bank contacts associated with the line of the called substation A² which we will assume are the bank contacts 386-389, inclusive. Slow acting 105 relay 516 is energized in multiple with the rotary magnet and operates at armature 110 546 to connect the test wiper 382 to the test relay 515.

Should the desired line be busy there will 115 be a ground potential present upon the test contact 388 and the test relay 515 will be 120 energized. Relay 515 upon energizing, establishes a locking circuit for itself at its armature 540 and at armature 543 places the 125 busy tone on the line of the calling subscriber. Upon hearing this tone the calling subscriber will replace his receiver upon the switchhook and the main dual connector H² will be released in the usual manner.

Should the calling substation A² be one 130 in a group of telephones listed under one

number the automatic rotation of the connector H^2 in which an idle line is selected will take place in the same manner as was described in connection with the main dual connector H , Fig. 1.

It will now be assumed that the line of the substation A^2 was idle when connection thereto was attempted. Under these conditions the test contact 388 will be ungrounded and no circuit will be completed for the test relay 515. Then, following the deenergization of the slow acting relay 516, a circuit will be traced extending from ground on release trunk conductor 307 by way of off normal spring 364 and its working contact, conductor 418, off normal spring 565 and its resting contact, normally closed springs controlled by armature 530, armature 540 and its back contact, conductor 438, upper winding of the switching relay 317, back contact and armature 342, conductor 430, back contact and armature 546, conductor 437, normally closed springs controlled by armature 351, test wiper 382, test contact 388, through the winding of the switching relay 395 of the line switch C^2 and through the winding of the stepping magnet 396 to battery. Relays 317 and 395 are energized over this circuit. The switching relay 395 is only partially operated, that is, enough to disconnect the line of the called substation from its normal battery and ground connections in the line switch C^2 . Switching relay 317 upon energizing, establishes a locking circuit for itself at armature 352 and at armatures 348 and 353 completes the ringing circuit. Ringing current is intermittently projected over the line of the substation A^2 . When the called subscriber answers the ring cut off relay 316 will be energized over the line of the called subscriber. Upon operating relay 316 at armature 343 establishes a locking circuit for itself and at armatures 340 and 345 opens the ringing circuit and at the front contacts of these armatures finally completes the talking connection. The back bridge relay 313 is also energized over the called subscriber's line loop. Upon operating, this relay completes the circuit of the slow acting relay 312 and that of the slow acting supervisory control relay 311. Relay 312 operates to prepare the impulsing circuit of the auxiliary connector H^2 and relay 311 operates to reverse the battery over the incoming trunk line whereby an operator is given supervision or a metering device at the calling substation operated.

Should the called subscriber at substation A^2 find it desirable to call another party in the branch exchange he will operate his calling device for the digits of the subscriber's number. By the operation of the calling device at substation A^2 a series of interruptions is produced in the circuit of the

back bridge relay 313 which deenergizes a plurality of times in response thereto. At each deenergization an impulse of current is sent over the following path: From ground by way of armature 332 and its 70 back contact, armature 330 and its front contact, conductor 440, off normal springs 570 and 569, winding of the vertical magnet 561, conductor 419, front contact and armature 328, conductor 417, and thence through 75 the winding of the slow acting relay 513 to battery. The above is the circuit over which the first impulse to the vertical magnet 561 is sent. Upon the first vertical step of the auxiliary connector H^2 the off normal 80 springs are shifted and the remaining impulses to the vertical magnet are sent over a new circuit which is the same as the one above traced except that it includes the off normal springs 570 and 571, and armature 85 531 and its front contact, relay 513 being now energized. Magnet 561 operates in the usual manner to raise the switch wipers of the auxiliary connector opposite the level corresponding to the digit called. Slow 90 acting relay 513 is energized in series with the vertical magnet and remains so throughout the vertical operation of the switch. Shortly after the termination of the operation of the vertical magnet the slow acting 95 relay 513 deenergizes and transfers the impulsing circuit to the rotary magnet 562.

The called subscriber at substation A^2 may now operate his calling device in accordance with the last digit of the desired subscriber's number. The back bridge relay 313 responds to the interruptions in its line circuit and will deenergize a plurality of times, each time sending an impulse of current over a circuit extending from ground by way of armature 332 and its back contact, armature 330 and its front contact, conductor 440, off normal springs 570 and 571, armature 531 and its back contact, conductor 420, working contact of off normal spring 366 and the said spring, conductor 432, armature 541 and its back contact, conductor 429, armature 349 and its front contact, conductor 435, off normal 100 spring 567 and its working contact, armature 555 and its back contact, and through the winding of the rotary magnet 562 to battery. Magnet 562 operates to rotate the wipers 580-583, inclusive, into engagement with the set of bank contacts associated with the line of the called substation which we will assume are the bank contacts 585-588, inclusive, associated with the line of the substation A^2 . Slow acting relay 516 is energized in multiple with the rotary magnet 105 and operates to connect the test wiper 582 to the test relay 515.

Assuming that the desired line is idle there will be no ground potential present upon the test contact 587 and consequently 110

no circuit will be completed for the test relay 515. Then, following the deenergization of the slow acting relay 516, a circuit is completed extending from ground on release trunk conductor 307, off normal spring 364 and its working contact, conductor 418, off normal spring 565 and its working contact, normally closed springs controlled by armature 530, armature 540 and its back contact, upper winding of the switching relay 517, conductor 436, front contact and armature 342, conductor 430, back contact and armature 546, normally closed springs controlled by armature 552, test wiper 582, test contact 587, winding of the switching relay 590 of the line switch C³, and through the winding of the stepping magnet 591 to battery. Relay 590 upon operating, clears the line of the called substation from its normal battery and ground connections in the line switch C³. Relay 517 upon energizing, establishes a locking circuit for itself at armature 553 and at armatures 550 and 556 completes the ringing circuit whereby the called subscriber is intermittently signaled. When the called subscriber at substation A³ removes his receiver from the switchhook, ring cut off relay 514 will be energized. Upon operating, this latter relay completes a locking circuit for itself at armature 536 and at armatures 534 and 538 completes the talking connection. The back bridge relay 511 is also energized over the line loop of the called subscriber and operates to complete the circuit of the slow acting relay 510 and also that of the supervisory control relay 311. Relay 510 upon energizing, completes a circuit extending from the tone machine, front contact and armature 329, conductor 415, armature 521 and its front contact, lower winding of the back bridge relay 511, and thence to the lower talking conductor of the auxiliary connector H³. This tone is audible to the two called subscribers and serves to inform them that there are three parties on the line. This provision is made so that one called party cannot remain on the line without the knowledge of the other subscriber. It will also be noted that upon the first off normal step of the auxiliary connector H³ the relay 318 is energized and it establishes a locking circuit for itself at armature 320 and at armature 319 completes the locking circuit of the supervisory control relay 311. The called subscriber at substation A² is therefore able to replace his receiver upon the switchhook without restoring the normal polarity of the battery over an incoming trunk and thereby preventing it from giving a disconnect signal to an operator if one is included in the connection. Conversation may now be carried on between the subscribers over the heavy talking conductors.

Should the subscriber at substation A² at

any time desire to retire from the connection he may do so by replacing his receiver upon the switchhook. The back bridge relay 313 is accordingly deenergized and the circuit of the slow acting relay 312 is opened. Upon relay 312 deenergizing a circuit is completed extending from ground by way of armature 332 and its back contact, armature 330 and its back contact, armature 344 and its front contact, conductor 433, armature 554 and its front contact conductor 427, working contact of off normal spring 365 and the said spring, and thence through the winding of the release magnet 356 to battery. Magnet 356 operates to restore the main dual connector H² to normal. Immediately upon operating the release magnet also opens the locking circuits of the ring cut off relay 316 and the switching relay 317.

Should the called subscriber at substation A³ desire to disconnect himself from the connection he may do so by replacing his receiver upon the switchhook. The back bridge relay 511 is then deenergized and the circuit of the slow acting relay 510 is opened. Upon the deenergization of the latter relay, a circuit is completed extending from ground by way of armature 522 and its back contact, armature 520 and its back contact, front contact and armature 537, conductor 425, armature 350 and its front contact, conductor 426, working contact of off normal spring 568 and the said spring, and thence through the winding of the release magnet 560 to battery. Magnet 560 operates in the usual manner to restore the auxiliary connector H³ to normal and the subscriber at substation A³ is accordingly released from the connection.

Should the line of the called subscriber at substation A³ be busy or should the calling subscriber at substation A² desire for any reason to release the auxiliary connector H³ prior to the time connection was made to the line of the called substation he would replace his receiver upon the switchhook, the relays 313 and 312 would deenergize, and a circuit would be completed extending from ground by way of armature 332 and its back contact, armature 330 and its back contact, front contact and armature 344, conductor 433, armature 554 and its back contact, working contact of off normal spring 568 and the said spring, and through the winding of the release magnet 560 to battery. Upon the operation of the release magnet the auxiliary connector H³ would be restored to normal.

Should the subscriber at substation A² not desire to hold the line until the answer of the subscriber at substation A³ he would replace his receiver and the main connector H² would be released in the same manner as was described when the subscriber at substation A² desired to retire from the three party connection. The normal battery flow over the incoming trunk line would not be re-

stored, however, as at this time the relay 318 would be locked energized as would the supervisory control relay 311.

It will now be assumed that after the subscriber at substation A² had retired from the three party connection the subscriber at substation A³ desired to call another party for the calling subscriber. In order to do this he would operate his calling device for the 10 digits corresponding to the number desired. By the operation of the calling device at substation A³ a series of interruptions is produced in the circuit of the back bridge relay 511 which deenergizes a plurality of 15 times in response thereto each time sending an impulse of current over the following circuit: From ground by way of armature 522 and its back contact, armature 520 and its front contact, conductor 413, off normal 20 springs 368 and 367, winding of the vertical magnet 357, back contact and armature 328, conductor 417, and thence through the winding of the slow acting relay 513 to battery. Upon the first vertical step of the switch the 25 off normal springs are shifted and the remaining impulses to the vertical magnet travel over a new circuit which is the same as the one traced above except that it includes the off normal springs 368 and 369, conductor 421, armature 531 and its front contact, and conductor 422, relay 513 being now energized. Magnet 357 operates to raise the switch wipers of the main dual connector opposite the level of the bank contacts in 35 which is located the contact set associated with the line of the desired substation. Slow acting relay 513 is energized throughout the vertical movement of the switch and at its termination deenergizes transferring the impulsive circuit to the rotary magnet 355.

The subscriber at substation A³ may now operate his calling device in accordance with the final digit of the desired subscriber's number. Back bridge relay 511 again responds to the interruptions in its line circuit each time sending an impulse of current over the following path: From ground by way of armature 522 and its back contact, armature 520 and its front contact, conductor 413, off normal springs 368 and 369, conductor 421, armature 531 and its back contact, conductor 420, working contact of off normal spring 366 and the said spring, conductor 432, armature 541 and its back 55 contact, conductor 429, armature 349 and its back contact, and through the winding of the rotary magnet 355 to battery. Magnet 355 operates to rotate the switch wipers 380—383, inclusive, into engagement with the contact set associated with the line of the called substation. The slow acting relay 516 is energized in multiple with the rotary magnet and operates to connect the test wiper 382 to the test relay 515.

Should the desired line be busy there will

be a ground potential upon the test contact engaged by test wiper 382 and the test relay 515 will be energized and the busy tone given to the subscriber. Should the line of this called substation be one of a 70 group of lines the automatic operation of the connector H² by which an idle line is selected will take place in the same manner as was described hereinbefore.

Assuming that the desired called line is 75 not busy there will be no ground potential upon this test contact and no circuit will be completed for the test relay 515. The subsequent operations of the main connector H² by which the called subscriber is signalled and the connection released will take place in the usual manner. It will be noted that upon the first off normal step of the connector H² that the relay 318 is energized and operates to control the supervisory relay 311 in the same manner as before.

As before mentioned, the incoming trunk line comprising conductors 305 and 306 is a two way trunk line and is adapted to be seized by a local connector selector repeater. When this occurs ground will be placed on release trunk conductor 376 which extends by way of armature 338 and its back contact, through the winding of relay 310 to battery. The relay 310 is thereby energized and operates to disconnect the trunk line comprising conductors 305 and 306 from the dual connectors H² and H³ and transfers it into connection with the local connector selector repeater. The trunk line may now be used for a call to the main exchange in the usual manner.

Having fully described and ascertained the features of the invention, what is considered to be new and desired to have protected by Letters Patent will be pointed out in the appended claims.

What I claim is:—

1. In a telephone system, automatic connector switches, called lines accessible thereto, means for operating either one of said switches vertically and for then rotating the same into connection with one of said called lines, a relay common to said automatic connector switches, and means for energizing said relay only during the rotation of whichever switch is being operated for initiating the testing of said called line.

2. In a telephone system, automatic connector switches, called lines accessible to said switches and divided into groups, means for operating either one of said switches in accordance with the two final digits in a called telephone number to select a desired group of lines, and means including relay mechanism common to said switches for causing the operated connector switch to select the first idle line in the selected group.

3. In a telephone system, a plurality of

subscribers' lines, a pair of connectors adapted to establish connection with said lines, relay mechanism common to said connector switches, said relay mechanism being 5 normally adapted to control the operation of the shaft and wipers of a particular one of said connectors in accordance with a digit in a telephone number for establishing a connection with a line, and means for then 10 disconnecting the relay mechanism from the operated switch and for connecting it with the other connector switch while the first is maintained in operated position.

4. In a telephone system, a pair of automatic connector switches, called lines accessible thereto, means for operating one switch of said pair into connection with one of said called lines, means controlled by the subscriber on the connected called line for 15 then operating the other switch of said pair into connection with another of said called lines, the control being exercised over a circuit including wipers of said first switch, and a relay common to said pair of switches 20 for supplying talking current to each of the subscribers on said called lines.

5. In a telephone system, a pair of automatic connector switches, called lines accessible thereto, means for operating one switch 30 of said pair into connection with one of said called lines, means controlled by a subscriber on the called line for then operating the other switch of said pair into connection with another of said called lines while maintaining the first switch in operated position, 35 and a busy test relay common to both switches of said pair for testing said called lines.

6. In a telephone system, a pair of automatic connector switches, called lines accessible thereto, means for operating one switch of said pair into connection with one of said called lines, means controlled by the subscriber on the connected called line for then 40 operating the other switch of said pair into connection with another of said called lines, the control being exercised over a circuit including wipers of said first switch, a relay common to said pair of switches for supplying talking current to each of the subscribers on said called lines, and a second 45 relay energized upon the operation of said common relay for controlling supervision.

7. In a telephone system, a pair of automatic connector switches, called lines accessible thereto, means for operating one switch of said pair into connection with one of said called lines, means controlled by the subscriber on the said called line for operating 50 the other switch of said pair into connection with a second called line, means for applying ringing current to the second called line, a relay energized upon the response of the second called subscriber for disconnecting 55 said ringing current, and a release circuit

completed by the operation of said relay for releasing the first switch of said pair.

8. In a telephone system, called subscribers' lines, a pair of automatic switches having access to said lines, means for operating one of said switches into connection with one of said lines, means under the control of the subscriber on the said called line for operating the other of said pair of switches into connection with another of said lines, the control being exercised over a circuit 70 including the wipers of said first switch, a test relay common to both of said connector switches and means for operating said relay when either of said pair of switches engages 75 a busy called line.

9. In a telephone system, a pair of automatic connector switches, calling and called lines, means under the control of a subscriber on one of said calling lines for operating one switch of said pair into connection with one of said called lines, a relay energized upon the response of the subscriber on the said called line for reversing the direction of current flow over the said calling 80 line, means under the control of the subscriber on said called line for operating the other switch of said pair into connection with another of said called lines, a second 85 relay energized upon the operation of said second connector switch for closing a locking circuit for said first relay, and means for opening said locking circuit upon the response of the subscriber on said second 90 called line.

10. In a telephone system, an automatic connector switch, called lines divided into groups accessible thereto, a test wiper for said switch, means for operating said switch vertically and for rotating it into connection 105 with one of said called lines, a relay, a second relay energized during the rotation of said switch for connecting said test wiper to said first relay, a second test wiper for said switch, means controlled by said second test wiper for initiating an automatic rotation of said switch if said connected called 110 line is busy, and means for opening the circuit of said second relay in order to prevent its energization during the automatic operation of said switch.

11. In a transfer call system, a main connector for extending a connection to a called line, an auxiliary connector controlled by the subscriber on the called line for passing 120 the call from said called line to a second called line, operating magnets for each connector, and a relay common to said connectors for shifting the operating circuits of either connector when the same is operated.

12. In a transfer call system, a main connector for extending a connection to a called line, an auxiliary connector controlled by the subscriber on the called line for passing the 125 call to a second called line, primary and secondary

- ondary operating magnets in each connector, an operating circuit, and a relay effective when either connector is being operated to shift the operating circuit from the primary magnet to the secondary magnet. 5
13. In a transfer call system, a main connector for extending a connection to a called line, an auxiliary connector controlled by the subscriber on the called line for passing the 10 call to a second called line, primary and secondary operating magnets in each connector, and a common stepping relay for controlling the secondary magnets of both switches.
14. In a transfer call system, a main connector for extending a connection to a called line, an auxiliary connector controlled by the subscriber on the called line for passing the 15 call to a second called line, primary and secondary operating magnets in each connector, 20 circuits for automatically operating the secondary magnets, and a plurality of common relays for controlling said circuits.
15. In a transfer call system, a main connector for extending a connection to a called line, an auxiliary connector controlled by the subscriber on the called line for passing the 25 call from said called line to a second called line, a test relay common to said connectors, and circuit connections for operating 30 said relay in case either called line is busy.
16. In a transfer call system, a main connector for extending a connection to a called line, an auxiliary connector for passing the call to a second called line, a test wiper for 35 each connector, and a conductor normally conductively connecting said wipers directly together.
17. In a transfer call system, a main connector for extending a connection to a 40 called line, an auxiliary connector controlled by the subscriber on the called line for passing the call to a second called line, a battery feed relay common to said connectors, circuit connections from said relay for supplying current to the first called line before the 45 call is passed and for supplying current to the second called line after the call is passed.
18. In a telephone system, a pair of automatic connector switches, called lines accessible thereto, means for operating one switch 50 of said pair into connection with one of said called lines, means for then operating the other switch of the pair into connection with a second called line, means for applying 55 ringing current to the second called line, a relay energized upon the response of the second called subscriber for disconnecting said ringing current, and a release circuit completed by the operation of said relay for 60 releasing the first switch of the pair.
19. In a telephone system, called lines, a 65 pair of connector switches, means for operating either switch into connection with one of said called lines, means for thereafter operating the remaining switch into connec-
- tion with another one of said lines, means for applying signaling current to the last called line, and a relay operative upon the response of the second called subscriber to cut off the signaling current and to close and 70 release circuit of the first operated switch.
20. In a telephone system, calling and called lines, a pair of connector switches having access to said called lines, means for setting up a connection to one of the called 75 lines via one of said switches, means for then transmitting signaling current to the line called, a relay in the switch used operative upon the called subscriber responding to cut off said signaling current and to close 80 a point in its own restoring circuit, means for then operating the second switch of said pair to establish a connection with a second called line, and a corresponding relay in the last operated switch operative contingent upon a response being received over the last line called to complete the restoring circuit.
21. In a telephone system an established connection between a calling and a called line, the connection including one of a pair of automatic switches, means under the control of one of said lines for causing a connection to be established between the other line and a third line, said connection including 90 the other automatic switch, release circuits for said automatic switches, and means operative contingent upon a response occurring on the second called line for completing said circuits. 95
22. In a telephone system, calling and called lines, a pair of automatic switches having access to certain of said lines, means for completing a talking connection between calling and called ones of said lines, means controlled over one of the lines in the established connection for establishing a talking connection between the other line and a second called line, restoring circuits for said switches, means for closing said circuits 100 operative upon response of the second subscriber called, and means for preventing the release of the last operated switch at this time. 105
23. In a telephone system, a trunk line terminating in a pair of directively controlled automatic switches, means for operating one of said switches into connection with a called line, a relay energized upon the response of the called subscriber to reverse the direction of current flow over said trunk, means for operating the other switch of the pair into connection with a second line, and a second relay for closing a locking circuit for said first relay responsive 110 to the operation of the other switch. 115
- In witness whereof, I hereunto subscribe my name this 31st day of March A. D., 1921.
- JOHN E. GARDNER.
